Primary Examiner — Kelley Donnelly(74) Attorney, Agent, or Firm — DASCENZO Intellectual Property Law, P.C.(57) CLAIM

The ornamental design for a handheld snack container, as shown and described.

DESCRIPTION

FIG. 1 is a front, top, right isometric view of the new design.

FIG. 2 is a top view of the new design.

FIG. 3 is a bottom view of the new design.

FIG. 4 is a right side view of the new design, with the left side view being the mirror image thereof.

FIG. 5 is a front view of the new design; and,

FIG. 6 is a rear view of the new design.

The shading lines shown in the drawings represent the approximate three-dimensional contour of the claimed design and are not intended to indicate surface decoration.

1 Claim, 3 Drawing Sheets(56)
